UNITED STATES PATENT OFFICE.

ELLSWORTH J. LIGHT, OF PITTSFIELD, MASSACHUSETTS.

ROCKER.

SPECIFICATION forming part of Letters Patent No. 689,977, dated December 31, 1901.

Application filed March 18, 1901. Serial No. 51,741. (No model.)

To all whom it may concern:

Be it known that I, ELLSWORTH J. LIGHT, a citizen of the United States, and a resident of Pittsfield, in the county of Berkshire and State 5 of Massachusetts, have invented new and useful Improvements in Rockers, of which the following is a specification.

My invention relates to the rockers of rocking-chairs; and it consists in the novel construction of the tread-piece of the rocker and the combination, with the rocker and tread-piece, of a novel device for securing the latter to the former, as will be hereinafter fully set forth, and pointed out in the claims.

15 The objects of my invention are to provide, with the rockers of rocking-chairs, an elastic tread-piece whereby the rockers when in operation on a floor will not travel over the floor and may be operated in direction transverse to the joints of the floor-boards without jar or shocks and be employed on polished and oiled floors without marking or marring the surface of the same and be rocked in part on a mat on the floor and in part on an un-matted portion of the floor without the occupant of the rocking-chair being conscious of an unevenness of the surface rocked on, and also to provide means for securing the elastic tread-piece to the rocker or to a piece on which 25 the rocker may oscillate.

30 Other objects and advantages of the invention will be fully understood from the following description and claims when taken in connection with the annexed drawings, in which—

Figure 1 is a perspective view of a rocker of a rocking-chair embodying my improvements. Fig. 2 is a longitudinal section of the same. Fig. 3 is a transverse section at line 40 1 in Fig. 2. Fig. 4 is a transverse section taken at line 2 in Fig. 2. Fig. 5 is a section, on enlarged scale, taken at line 2 in Fig. 2 and illustrating the invention and a preferred form of longitudinal perforation provided in 45 the elastic tread-piece. Fig. 6 is a view of the preferred means for securing the said tread-piece on the rocker. Fig. 7 is a section showing a modification of the longitudinal perforation which may be provided in said 50 elastic tread-piece, and Fig. 8 is a view of an exterior form of said tread-piece which may be given to it.

Similar letters of reference refer to similar parts throughout the several views.

In the drawings, A is a rocker of a rocking-chair.

B represents the legs to which the rocker is secured.

C is the groove for receiving the elastic tread-piece D, which groove may be concave 60 in form, as shown in Figs. 3, 4, and 5, or be made with a horizontal flat-bottom-form groove C', as in Fig. 8, either of which forms being adapted to retain said tread-piece D from shifting sidewise.

65 D is the elastic tread-piece, made of elastic rubber and preferably round in form in its cross direction, as shown in Figs 3, 4, and 5, and made with a suitable length for correspondence with the length of the groove C, provided in the lower side of the rocker, when said tread-piece is suitably stretched and applied to the rocker, to give it a suitable contractile tension between its secured ends, and thereby cause the said tread-piece to hug 70 close and hard on the bottom of said groove and prevent it from crawling alternately in opposite directions when the rocker is being oscillated under weight of an occupant. This elastic tread-piece D is perforated longitudinally from one end to the other by a perforation made with any suitable form in cross direction for receiving a suitable clamping-nut, yet I at present prefer to make said perforation either oval, as d in Fig. 5, or rectangular, as in Fig. 7, and with its longest diameter vertical, as shown in said Figs. 5 and 7, while an oblong nut, as shown in Fig. 6, is my preferred form of clamping-nut, whether made in cylindrical form, as E in Fig. 5, or 80 with a square form, as E', when the perforation is of rectangular form, as shown in Fig. 7. These oblong clamping-nuts E and E' are each provided at a suitable point in its length with a screw-threaded perforation e, made in 85 direction transverse to its length, as indicated by dotted lines in Fig. 6. These nuts E E' are introduced in the perforation d, one near each end of the tread-piece, as shown in Fig. 2. Screw-bolts F, passing through 90 perforations f, provided through the rocker A and passing through perforation d', provided in the upper side wall portion d² of the said tread-piece D and screwing into the

100

screw-threaded perforation e of said nuts, securely hold the respective outer end portions of the said piece, by means of said upper side wall portion d^2 , tightly clamped 5 against the face-surface of the groove-form seat C. When the oblong clamping-nuts are inserted properly in place in the perforation d in said elastic tread-piece D and the binding screw-bolts F are tightly screwed, respectively, 10 into said nuts, the said nuts will be drawn tight against the upper side wall portion of the said perforations and become sunken therein, so as to be out of touch from the lower inner side of the wall of said perforations, as illustrated in Figs. 5 and 7. This clearance of the lower side of the nuts E or E' from touch of the lower inner side of the lower side portion or wall of the elastic tread-piece may be produced, but to a less 20 degree, when the screw-bolt F is so tightly screwed into the said binding-nut as to cause the latter to indent the material of the upper side portion d^2 of the wall in direction from the perforation d toward the face of the groove 25 C, as shown in Fig. 8. J J, Fig. 2, are end-closing straps, which have their lower ends of form of a semicircle of diameter corresponding with that of the said tread-piece D and are cemented on the outer end surfaces 30 of the said piece by rubber cement, so as to close over the ends of perforation d , and have each a portion j extended to a suitable distance above the groove-form seat of the rocker and may be secured to the material of the 35 same by suitable nails.

M M are metal keepers, one shown in perspective in Fig. 1 and both in section in Fig. 2. These keepers extend from the point of upper side of the tread-piece D and are placed 40 over the upwardly-extended portions of the said end-closing strips and secured to the ends of the rocker by means of nails or screws which also pass through the upper end portions j of strips J, as shown in Fig. 2.

45 The manner in which I prefer to apply this elastic tread-piece to the rocker is as follows: The groove-form seat C having been formed in the rocker from its lower side and the ends of the said rocker having been perforated to 50 receive the perforation f for passage of the screw-bolts F from the upper edge to the said seat of the rocker and the elastic tread-piece D having been cut to a suitable length—say an inch and a half shorter than the length of 55 the said groove-form seat—the oblong nuts E will be inserted into one end of the perforation d of said elastic tread-piece to a short distance, so as to carry its screw-threaded perforation e opposite the perforation d^2 , made 60 in the upper side wall of the said tread-piece, when the screw-threaded end of bolt F at said end will be passed through said perforation d^2 and be entered into the screw-threaded hole e and be turned in suitable direction so 65 as to be screwed in said nut E. The opposite end of said tread-piece will be perforated through its upper side wall portion at a point

back from the outer end thereof equal to the distance the lower end of the screw-receiving perforation f is from the opposite end of the 70 groove-form seat, and the second oblong nut E will be inserted in place with its screw-threaded perforation e registering with the screw-threaded perforation d^2 of the upper side wall portion of said piece, when the operator will pull lengthwise on said elastic tread-piece and stretch the same, so as to carry perforation d^2 in said upper side wall and screw-threaded perforation e of said nut E to opposite the lower end of bolt F and then 75 screw the latter into the said nut. These two bolts F will now be tightly screwed into their respective nuts and cause the latter to be drawn and clamped hard against the inner surface of the upper side of perforation d , 80 when the lower side of said nuts will be drawn toward the upper side wall portion of the tread-piece and out from touching the lower side wall portion of the same. The operator will now trim the two opposite ends of the 85 said tread-piece D and cement the strips J to said ends and carry their respective end portions j over the ends of the rocker and then apply the metal keepers M M over said end portions j of said strips and secure them in 90 place by the nails or screws. When an occupant of the chair is rocking in the same, his weight on the said elastic tread-piece of the rocker will distend the two lateral side portions of its elastic wall and also flatten to 95 a degree the lower surface of said piece wherever in its length it comes in contact with the surface rocked on. This elastic tread-piece prevents the rocker from moving in the least in any direction in relation to the floor, 100 and the oscillations of the rockers will be noiseless, and a marring of the floor, mat, or carpet by the rockers will be prevented.

Having described my invention, what I claim, and desire to secure by Letters Patent, 105 is—

1. The combination with an elastic tread-piece having longitudinally through it from one end thereof to the other the nut-receiving perforation described, and also having 110 through a portion of the wall surrounding the said longitudinal perforation, a screw-receiving perforation of diameter smaller than that of the said longitudinal perforation and communicating with the latter, of a clamping-nut adapted to be moved in either direction within said longitudinal perforation and in 115 relation to the said smaller screw-receiving perforation corresponding with that of the latter and having a length outward in opposite direction from its screw-threaded perforation greater than that of said nut-receiving perforation, and a screw-bolt adapted to be 120 passed through a piece to which said tread-piece is to be secured and through the said screw-receiving perforation in the latter and into the said screw-threaded nut, as set forth.

2. The combination with the elastic tread-piece D, of length described, having through

it from end to end a nut-receiving perforation of diameter of greater length in one direction than in another and having through a wall portion thereof in direction of the longest diameter of said perforation two bolt-receiving perforations, described, which communicate at two points in its length from an outer side of the same to the chamber of said nut-receiving perforation of two oblong nuts having their screw-threaded perforations running transverse to their direction of length and adapted to be received into said nut-receiving perforations and register with the said bolt-receiving perforations and binding screw-bolts of length adapted to be passed through suitable perforations provided in a rocker and through said bolt-receiving perforations, whereby they may respectively be screwed

into said nuts as and for the purposes set forth.

3. The combination with a rocker having a groove-form seat in its lower side, and bolt-receiving perforations vertically through its end portions, of the elastic tread-piece D having through it the described nut-receiving perforation d, and screw-bolt receiving perforation d', oblong screw-threaded clamping-nuts, screw-bolts F screwing in said clamping-nuts, end-closing strips and metal keepers over the respective extended portions of said strips for the purposes set forth.

ELLSWORTH J. LIGHT.
